UNITED STATES PATENT OFFICE.

OWEN J. WILLIAMS, OF ORCHARD PARK, NEW YORK.

SOCKET WRENCH.

1,413,444.

Specification of Letters Patent. Patented Apr. 18, 1922.

Application filed June 11, 1921. Serial No. 476,679.

To all whom it may concern:

Be it known that I, OWEN J. WILLIAMS, a citizen of the United States, and a resident of Orchard Park, in the county of Erie and State of New York, have invented a new and Improved Socket Wrench, of which the following is a full, clear, and exact description.

This invention relates to improvements in socket wrenches, of the general character disclosed in my application for Patent Serial No. 410,148, allowed December 16, 1920.

An object of this invention is to provide a wrench in which the jaws are firmly compressed against torsional strain, and to provide an improved actuating means for the jaws.

A still further object is to illustrate various slight changes and improvements in the wrench which tend to make it more durable and efficient in use, more simple and practical in construction, and to lessen its cost of manufacture.

With these and other objects in view, the invention consists in certain novel features of construction and combinations and arrangements of parts as will be more fully hereinafter described and pointed out in the claims.

30 In the accompanying drawings:—

Figure 1 is a view in side elevation of my improved wrench;

Figure 2 is a view in longitudinal section therethrough illustrating the jaws in contracted position;

Figure 3 is a view similar to Figure 2, illustrating the jaws in expanded position to receive a large sized nut;

Figure 4 is a cross sectional view through the wrench on the line 4—4 of Figure 2;

Figure 5 is a bottom plan view of Figure 3;

Figure 6 is a top plan view of Figure 1;

Figure 7 is a bottom plan view of Figure 1; and

Figure 8 is a fragmentary view in section through the casing illustrating a slightly modified form of a handle member for operating the screw.

50 Referring in detail to the drawings, 1 represents a substantially cylindrical casing, internally screw threaded and reduced at one end, as indicated at 2, and of the external angular shape at its other end, designated by the reference numeral 3. The angular outer end of the casing may conveniently re-

ceive any suitable tool for turning the wrench. A screw 4 fits within the upper end of the casing and includes a reduced upper end 5, knurled or milled, as indicated at 6, to facilitate the manual adjustment of the screw 4. Adjacent its lower end, the screw 4 includes a reduced portion 7 and terminates in an enlargement 8, the screw being formed with a rounded annular shoulder 9 between the reduced portion and its enlarged extremity.

The inner lower end of the casing is formed with a plurality of vertical grooves 10 extending from the threaded portion of the casing to the rounded lower edge thereof. A series of jaws 11 are arranged to form a socket and each jaw includes an inwardly presented rounded shoulder 12 which fulcrums on the shoulder 9. The jaws are also formed with outwardly presented curved ribs 13 fitting within the grooves 10 and bracing the jaws against torsional strain. The rounded lower edge of the casing 1 limits the outward movement of the jaws 11. 80

The jaws preferably include flat faces 14 adjacent their lower extremities for the accommodation of a small sized nut and curved interior faces such as 15 adjacent their intermediate portions for the accommodation of a larger sized nut, such as the nut 16 illustrated in Fig. 2.

The invention in this case resides partially in the provision of a novel actuating means for the jaws. Each jaw adjacent its inner end is notched or grooved, as indicated at 17 and a circular contraction spring 18 is accommodated in the grooves.

The operation of the device will be readily understood. The spring 18 normally tends to hold the inner ends of the jaws together and expand the outer ends of the jaws 11 which fulcrum on the shoulder 9. When the screw 4 is adjusted, the ribs 13 riding in the grooves 10 will be forced inwardly by the rounded lower end of the casing, so that as the screw 4 is moved toward the upper end of the casing, the jaws will be contracted.

It will be apparent that the shape of the inner faces of the jaws might be considerably varied to accommodate nuts of various sizes and that although I have shown a cylindrical casing and a hexagonal socket, the shape of the casing and socket and the number of jaws might also be changed to suit the trade. 105

In Figure 8, I have illustrated a slight

modification wherein the screw 4 is provided with a flattened upper end 19 forming a handle member which facilitates the easy manipulation of the screw.

5 In my previous application, each jaw included an angular inner face adapted to embrace one corner of a nut. With the form of device herein illustrated, each jaw includes a flat surface adapted to engage one 10 flat face of a nut. This feature, together with the torsional bearing above described adds greatly to the strength of the wrench.

15 Various slight changes and alterations might be made in the general form and arrangement of the parts described without departing from the invention and hence I do not wish to limit myself to the precise details set forth, but shall consider myself at liberty to make such slight changes and 20 alterations as fairly fall within the spirit and scope of the appended claims.

I claim:

1. In a socket wrench, a casing internally 25 screw threaded adjacent one end, a screw movable in the casing, a shoulder integral with the screw, a plurality of jaws cooperating to form a socket, shoulders on the jaws fulcruming on the first mentioned shoulder, a contraction spring tending to pull the inner 30 ends of the jaws together and expand the socket.

2. In a socket wrench, a casing internally 35 screw threaded adjacent one end, a screw movable in the casing, a shoulder integral with the screw, a plurality of jaws cooperating to form a socket, shoulders on the jaws fulcruming on the first mentioned shoulder, a contraction spring tending to pull the inner 40 ends of the jaws together and expand the socket, and means for positively limiting the expansion of the socket.

3. In a socket wrench, a casing internally 45 screw threaded adjacent one end, a screw

fitting within the casing, said screw including a reduced portion and a shoulder immediately below said reduced portion, a plurality of jaws fulcrumed on said shoulder and cooperating to form a socket, said casing having a plurality of vertical grooves 50 in its inner face, ribs on the jaws located in the grooves and bracing the jaws against torsional strain.

4. In a socket wrench, a casing, a screw movable longitudinally of the casing, a shoulder on the screw, a series of jaws 55 cooperating to form a socket and mounted to rock on the shoulder, and a contraction spring embracing the inner ends of all the jaws tending to expand the socket.

5. In a socket wrench, a casing screw 60 threaded adjacent one end, a screw in the casing, said screw including a reduced portion and a rounded shoulder below said reduced portion, an annular series of jaws 65 cooperating to form a socket, rounded shoulders on the jaws rocking on said first-mentioned shoulder, the inner ends of said jaws having notches therein, an annular contraction spring located in said notches and tending 70 to expand the socket.

6. In a socket wrench, a casing screw 75 threaded adjacent one end, a screw in the casing, said screw including a reduced portion and a rounded shoulder below said reduced portion, a plurality of jaws cooperating to form a socket, rounded shoulders on the jaws rocking on said first-mentioned shoulder, the inner ends of said jaws having notches therein, an annular contraction spring located in said notches and tending 80 to expand the socket, means whereby movement of the screw in one direction positively contracts the socket against the action of the contraction spring.

OWEN J. WILLIAMS.
